MULTIPLE ENGINE OUTPUT EQUALIZING APPARATUS

Arthur G. Larson, Forest Hills, Pa., assignor to
The Westinghouse Air Brake Company, Wil-
merding, Pa., a corporation of Pennsylvania

Application March 5, 1946, Serial No. 652,151

5 Claims. (Cl. 60—97)

1

This invention relates to control apparatus and more particularly to means for equalizing the power output of a plurality of prime movers such as internal combustion engines of the Diesel type.

In the copending application of James A. Campbell, Serial No. 654,931 filed March 16, 1946, and assigned to the assignee of the present application, there is disclosed a control system for a plurality of prime movers arranged to be controlled and operated in unison. The system embodies apparatus on one of the prime movers which is preconditioned to control apparatus on the other prime mover or prime movers to automatically cause operation of said other prime mover or movers to produce the same power output as from the one prime mover. In case the control apparatus on the one prime mover, which may be called a master, should fail however, or if for any reason the master prime mover should become inoperative, and it was desired to still operate the other prime movers, the power output of said other prime movers would not and could not be automatically equalized.

The principal object of the invention is therefore the provision of an improved control system for a plurality of prime movers, arranged to be operated in unison, in which any one of the prime movers can be selected to act as the master for causing equalization of the power output of all of the prime movers.

Other objects and advantages will be apparent from the following more detailed description of the invention.

In the accompanying drawings; Fig. 1 is a diagrammatic view of control apparatus for controlling the speed or power output of a plurality of prime movers and embodying the invention; Fig. 2 is a diagrammatic view of a portion of a fuel control system for each of said prime movers; Fig. 3 is a sectional view of a power or governor control motor for each of said prime movers and shown in elevation in Fig. 1; Fig. 4 is a sectional view of a pressure regulating valve device for each of said prime movers and shown in elevation in Fig. 1; and Fig. 5 is a sectional view of an equalizing valve device for each of said prime movers and shown in elevation in Fig. 1.

Description

As shown in Fig. 1 of the drawings, the dot-dash line enclosures, designated A and B, indicate two of any desired number of prime movers which it is desired to control and operate in unison. Each of the prime movers may, for the purpose of illustration, be of conventional Diesel en-

2

gine type comprising a cam shaft 1 (Fig. 2) for operating, through a cam 2 and a push rod 3, a fuel injector pump 4 for supplying fuel through an injector pipe 5 to a cylinder (not shown) of said engine. The amount of fuel supplied to the engine cylinder by pump 4 is adapted to be regulated by a pump adjusting rack 6 which is operatively connected to a lever 7 on a fuel control shaft 8. The fuel shaft 8 may have an engine 10 idling position in which it is shown in the drawing for adjusting pump 4 to provide fuel to the engine cylinder in an amount sufficient to cause operation of the engine at an idling speed, and may be turned in a clockwise direction, as viewed 15 in Figs. 1 and 2, to adjust said pump to increase the fuel supply in proportion to the degree of such turning. A maximum amount of fuel will be provided to the engine cylinder in a position of the fuel control shaft 8 such as indicated 20 by a dot-dash line 9. It will be understood that each engine may have any desired number of cylinders and that a fuel pump 4, rod 3 and cam 2 will be provided for each cylinder, and that the fuel shaft 8 will be connected to all of said pumps 25 in accordance with conventional practice.

Adjustment of the fuel control shaft 8 on each engine may be controlled by a speed governor 10 which may comprise a centrifuge 11 connected by gears 11a to the cam shaft 1. Two oppositely arranged centrifugally controlled governor arms in the form of bell cranks 12 are pivoted at their knees on pins 13 in centrifuge 11. One end of each of the bell cranks 12 engages a collar 14 secured to a vertically movable plunger or rod 15 which is provided with another collar 16 engaged 35 by one end of a governor control spring 17. The opposite end of spring 17 is engaged by a movable follower 18 against which bears an adjusting cam 19 pivoted on a fixed pin 20 and connected by an arm 21 to a governor adjusting rod 22.

When the engine is in operation turning cam shaft 1 centrifugal force of the governor bell cranks 12 will be opposed by the pressure of the control spring 17, and the upper end of said cranks will move away from rod 15 to a position 45 in which said centrifugal force will balance the pressure of said spring, to thereby position said rod in accordance with the pressure of said spring. If the cam 19 is turned in a counterclockwise direction (Fig. 2) to increase the pressure of spring 17 on collar 16 the upper ends of bell cranks 12 will be moved toward rod 15 to permit said rod to move down a proportional degree, while, if the cam is returned toward the position in which it is 50 shown in the drawing, the rod 15 will be ele-

vated correspondingly. In other words, when the engine is operating the rod 15 will assume a position corresponding to the adjustment of cam 19.

An operating arm 23 on the fuel control shaft 8 is connected by a link 24 to one end of a lever 25. The opposite end of lever 25 is fulcrumed on a fixed pin 26, while intermediate its end said lever is connected by pin 27 to the governor rod 15, whereby the fuel control shaft 8 will be positioned in accordance with the position of said rod and of cam 19.

In the drawing the parts of governor 10 including cam 19 and the fuel control shaft 8 are shown in positions which it may be assumed will provide for operation of the engine at an idling speed. If the cam 19 is turned from this idling position in a clockwise direction, the governor rod 15 and fuel control shaft 8 will move out of idling position to a new position, corresponding to the change in position of said cam, to cause a proportional increase in the amount of fuel supplied to the engine and thereby a corresponding increase in power output of the engine. Turning of cam 19 in the opposite direction will result in a corresponding reduction in the amount of fuel supplied to the engine. It will thus be seen that by suitable adjustment of cam 19 the supply of fuel to the engine may be adjusted to obtain any selected degree of power output from the engine.

At each engine the governor control rod 22 is operatively connected to a fluid pressure controlled power or governor control motor 28 which is arranged to control the respective speed governor 10.

Each of the fluid motors 28 comprises (Fig. 3) a casing containing a flexible diaphragm 29 clamped around its edge in the casing and having at one side a pressure chamber 30 connected to a pipe 31. At all of the engines the pipes 31 are connected to a common control pipe 32 leading to an operator's control valve device 33 which may be of any suitable structure for varying the pressure of fluid in said control pipe and thereby in pressure chambers 30 in the governor control motors 28 at all of the engines, simultaneously. At the opposite side of diaphragm 29 in each of the governor control motors 28 is a non-pressure chamber 34 which is in constant communication with atmosphere through a passage 35. An operating rod 36 disposed in non-pressure chamber 34 extends through the center of diaphragm 29. The rod 36 is provided in non-pressure chamber 34 with a follower 37 engaging the adjacent face of diaphragm 29, while mounted over said rod in pressure chamber 30 is a follower 38 and a clamping nut 39 having a screw-threaded engagement with said rod for clamping said followers and thereby said rod to the central portion of said diaphragm.

In each motor 28, the rod 36 extends to the exterior of the casing through a bore provided in a regulating nut 40 which extends into non-pressure chamber 34 for supporting one end of a regulating spring 41. The spring 41 encircles rod 36 and its opposite end bears against the follower 37 forming a part of said rod. The end of rod 36 extending out of the casing is pivotally connected by a pin 42 to a lever 43 intermediate its ends. One end of lever 43 is connected by a pin 44 to one end of a link 45, and the opposite end of the link 45 is pivotally connected, by a pin 46, to the casing of the device. The opposite end of lever 43 is operatively connected to the respective governor adjusting rod 22.

Each of the governor control motors 28 further comprises what may be called a vernier diaphragm

48 preferably of less area than diaphragm 29 and clamped around its edge in the casing and having at one side a pressure chamber 49 which is connected to a pipe 50. At the opposite side 5 of diaphragm 48 is a non-pressure chamber 51 containing a follower 52 engaging the adjacent side of said diaphragm. Projecting from follower 52 is a rod 53 the other end of which is pivotally connected to one end of a bell crank 54. The bell 10 crank 54 is pivoted at its knee on a pin 55 carried by an arm 56 projecting from the casing, while the opposite end of said bell crank is connected to pin 42 which connects rod 36 to lever 43. It will be noted that pressure of fluid in the vernier 15 diaphragm chamber 49 transmitted through bell crank 54 to rod 36 will oppose pressure of fluid in chamber 30 acting on diaphragm 29.

The pressure of regulating spring 41 in each of the governor control motors 28 against the diaphragm 31 is so adjusted by regulating nut 40 as to insure movement of said diaphragm and thereby of the rod 36 and lever 43 to their idling position, in which they are shown in the drawings, and which is defined by contact between the 25 follower plate 38 and a stop 57 in the casing, when pressure of fluid in diaphragm chamber 30 is at a chosen low degree. With the parts thus conditioned, the governor control cam 19 will assume its idling position in which it is shown in the drawing 30 for thereby conditioning the governor control spring 17 to permit operation of the engine at idling speed.

When, by operation of the operator's control device 33, fluid is provided in diaphragm chamber 35 30 of each of the governor control motors 28 at a pressure sufficient to overcome the opposing force of spring 41 plus pressure of fluid in chamber 49 acting on vernier diaphragm 48, the diaphragm 29 will be deflected against said spring 40 to rock lever 43 in a counterclockwise direction for actuating cam 19 to increase the pressure of spring 17 in the respective speed governor 10 an amount proportional to the movement of said diaphragm from its normal position and thus proportional to the increase in pressure of fluid provided through the control pipe 32 in diaphragm chamber 30, whereby the speed governor 10 on the respective engine will operate to correspondingly increase the supply of fuel to the engine. 45 If the pressure of fluid in diaphragm chamber 30 is further increased by the operator's control valve device 33 the diaphragm 29 will deflect further to correspondingly increase the pressure of the respective governor spring 17 for providing a corresponding increase in the amount of fuel supplied to the engine. On the other hand, to reduce the amount of fuel supplied to the engine, the pressure of fluid in diaphragm chamber 30 will be reduced, by operation of the operator's 50 control device 33, to a degree corresponding to the desired reduction in fuel supply, and the regulating spring 41 aided by pressure of fluid in chamber 49 acting on the vernier diaphragm 48 will then move the diaphragm 29 back to a position in which the pressure of said spring is reduced a degree corresponding to the reduction in pressure of fluid in chamber 30, whereupon movement of diaphragm 29 will cease. This movement of diaphragm 29 will in turn actuate cam 60 19 to reduce the pressure of the respective governor control spring 17 whereupon the speed governor 10 will operate to correspondingly reduce the amount of fuel supplied to the engine. If the pressure of fluid in diaphragm chamber 30 is sufficiently reduced to allow diaphragm 29 to be 65 70 75

returned to its idling position by regulating spring 41, the governor control cam 19 will be returned to its idling position to thereby permit operation of governor 18 to reduce the fuel supply to the respective engine to the degree required to permit operation of said engine at idling speed.

In the above described operation of the governor control motors 38 it was assumed that the vernier diaphragm chamber 48 was charged with fluid at some chosen pressure, but the pressure of fluid which may be effective in the vernier diaphragm chamber 49 of the several motors may be either greater or less than said chosen pressure which will be effective only on the engine selected as the master for causing equalization of the power output of all of engines, as will be hereinafter described in detail. It is however desired to point out that the position which diaphragm 29 in each of the motors 28 will assume when subject in chamber 30 to any chosen pressure of fluid will vary in proportion to the pressure of fluid effective in chamber 48 on the vernier diaphragm 48. It is further desired to point out that when the vernier diaphragm 48 in each of the motors 28 is subject in chamber 49 to fluid at the chosen pressure, which may be twenty-five pounds, the adjusted pressure of regulating spring 41 against the diaphragm 29 will be such that diaphragm 29 will promptly move from its normal or idling position, in which it is shown in the drawing, in response to an increase in pressure in chamber 30 above its normal minimum value.

Associated with each of the engines is a pressure regulating valve device 60 arranged to be controlled by the respective fuel control shaft 3 for providing in a pipe 61 fluid at a pressure proportional to the position of said shaft and hence proportional to the amount of fuel supplied to the respective engine.

Each of the pressure regulating valve devices 60 comprises (Fig. 4) a casing containing two spaced apart and coaxially arranged flexible diaphragms 62 and 63, of the same areas and clamped around their edges in the casing. Between the two diaphragms 62 and 63 is a chamber 64 open to a fluid pressure supply pipe 65 and thus adapted to be constantly supplied with fluid under pressure. The chamber 64 is formed in two parts separated by a wall 66 but in constant communication with each other through a passage 67 in said wall. At the opposite side of diaphragm 63 is a non-pressure chamber 68 which is open to atmosphere through a breather port 69. At the opposite side of diaphragm 62 is a chamber 70 open through a stabilizing choke 71 to a chamber 72 to which pipe 61 is connected.

Disposed in chamber 64 between the two diaphragms 62 and 63 is a stem 73 having one end connected to the center of diaphragm 63 by follower plates 74 and a clamping nut 75. The opposite end of stem 73 is in the form of an enlargement 76 extending centrally through the diaphragm 62 and cooperating with a nut 77 in chamber 70 to secure said stem to diaphragm 62 through the medium of follower plates 78. A coil regulating spring 79 encircling stem 73 in chamber 64 has one end engaging the casing wall 66, while the opposite end acts against the enlargement 76 through the medium of a spring follower 80. With spring 79 fully expanded, the diaphragms 62 and 63 and the stem 73 will assume a position such as that in which they are shown in Fig. 4 of the drawing.

In the stem enlargement 76 is a chamber 81 open through a passage 82 to the fluid pressure supply chamber 64. A fluid pressure supply valve 83 contained in chamber 81 has a fluted stem 84 extending through an axial bore in nut 77 into a chamber 85 formed within an extension 86 of said nut. The extension 86 is mounted to slide in a sleeve 87 which extends from the exterior of the casing through chamber 72 and a wall separating said chamber from chamber 70. Chamber 85 in the nut extension 86 is open through one or more ports 88 to chamber 72. A spring 89 contained in chamber 81 acts on the supply valve 83 for urging it into contact with a seat provided on the nut 77.

In chamber 85 the end of the supply valve stem 84 engages a fluid pressure release valve 90 having a fluted stem 91 mounted to slide in a bore provided axially of a plunger 92 which is slidably mounted in sleeve 87 above the nut extension 86, said plunger being provided around the end of said bore which opens to chamber 85 with a seat for engagement by said release valve. The release valve stem 91 extends into a chamber 93 in plunger 92, said chamber being in constant communication with atmosphere through registering ports 94 in said plunger and in the sleeve 87. Chamber 93 contains a bias spring 95 acting on the stem 91 of release valve 90 for urging said valve away from its seat, the pressure of said spring on said release valve stem being less than that of spring 89 on the supply valve 83. The plunger 92 has an annular groove carrying a sealing ring 96 having sliding contact with the interior surface of sleeve 87 for preventing leakage of fluid under pressure from chamber 85 past said plunger to atmosphere.

Outside of the casing and beyond the adjacent end of sleeve 87 is a spring seat 97 secured to plunger 92, and a coil spring 98 encircling said sleeve and supported on the casing bears against said seat for urging said plunger in a direction away from the release valve 90. Above the spring seat 97 an adjusting screw 99 is connected to plunger 92 by screw-threaded engagement and is locked in an adjusted position by a lock nut 100 mounted on said screw and engaging the adjacent end of said plunger. The adjusting screw 99 is engaged by one end of a bell crank 101 which at its knee is pivoted on a pin 102 carried in an arm 103 projecting from the casing. The opposite end of the bell crank 101 is operatively connected to one end of a link 104 the opposite end of which is connected to one end of an arm 105 which is mounted on the respective engine fuel control shaft 3 for movement therewith.

With the fuel control shaft 3 on each engine in its engine idling position, screw 99 in the respective regulating valve device 60 will be turned out of plunger 92 for urging said plunger in a downwardly direction against springs 98 and 95 to a position in which said plunger may contact the release valve 90, with the supply valve 83 seated by spring 89 and with the spring 79 fully expanded. The screw 99 may then be locked to the plunger 92 by the lock nut 100. If the fuel control shaft 3 on either engine is now rocked out of its idling position (Fig. 1 and 2) this movement will actuate arm 105 and link 104 to rock bell crank 101 of the respective pressure regulating device 60 in a corresponding direction and move plunger 92 in the direction of the supply valve 83, and with the release valve 90 seated against the end of said plunger,

said supply valve will be opened to permit flow of fluid under pressure from chamber 64 to chamber 85 and thence through port 88 to chamber 72 and the respective pipe 61. At the same time as fluid thus flows to pipe 61 it will equalize through the stabilizing choke 71 into chamber 70 and therein act on diaphragm 62 in opposition to pressure of the regulating spring 79.

When the pressure of fluid then supplied to chamber 70 becomes increased to a degree sufficient to overcome the force of regulating spring 79, the diaphragms 62 and 63 will deflect against said spring. Now assuming that movement of the respective fuel control shaft 8 has ceased in some position out of its idling position, movement of plunger 92 and thereby of the release valve 90 and supply valve 83 will also have stopped in a corresponding position, as a result of which, deflection of diaphragms 62 and 63 by increasing pressure of fluid in chamber 70 will be relative to said supply valve until said supply valve becomes seated. Seating of the supply valve 83 will then prevent further flow of fluid under pressure to chambers 72 and 70 and to pipe 61 whereupon deflection of diaphragms 62 and 63 will cease, since the pressure of the regulating spring 79 will have been increased sufficiently to counterbalance the pressure of fluid in chamber 70. The increase in pressure of fluid in pipe 61 will therefore be limited to a degree depending upon the extent of movement of the respective fuel control shaft 8 out of its idling position.

If the fuel control shaft 8 on either engine is turned further out of its idling position the respective pressure regulating valve device 60 will again be operated to increase the pressure of fluid in the respective pipe 61 to a degree corresponding to such movement. A maximum pressure of fluid will be obtained in each pipe 61 when the respective fuel control shaft 8 is moved to its full fuel position indicated by the dot-dash line 9.

On the other hand, if the fuel control shaft 8 on either engine is turned in the direction of its idling position, assuming that it is out of said position, this movement will, in the respective pressure regulating device 60, rock bell crank 101 to permit movement of plunger 92 by spring 98, plus pressure of fluid in chamber 85 acting on said plunger, in a direction away from the supply valve 83. With the supply valve 83 seated and stationary at this time due to pressure of fluid in chamber 70 counterbalancing the pressure of regulating spring 79 on diaphragm 62, the release valve spring 95 will hold the release valve 90 stationary with the supply valve 83 and against movement with plunger 92, so that this movement of said plunger will be away from said release valve to thereby open communication past said release valve for releasing fluid under pressure from chamber 72 and pipe 61 and also from chamber 70 above diaphragm 62 by way of stabilizing choke 71. As the pressure of fluid in chamber 70 is thus reduced the regulating spring 79 will deflect diaphragms 62 and 63 in the direction of plunger 92, and during such movement spring 89 will move the supply valve 83 and the release valve 90 along with said diaphragms. Assuming that the fuel control shaft 8 is now stopped in a position out of idling position, movement of plunger 92 will cease in a corresponding position, so that movement of the release valve 90 with the dia-

phragms 62 and 63 will then be relative to said plunger until said valve engages its seat for preventing further release of fluid under pressure from chamber 72, pipe 61 and chamber 70.

5 When the release valve 90 is thus closed, preventing further release of fluid under pressure from chamber 70, the diaphragms 62 and 63 will stop moving since the pressure of fluid in said chamber will just counterbalance the pressure of regulating spring 79. Thus the pressure of fluid in pipe 61 will only be reduced to a degree corresponding to the position of the fuel control shaft 8 out of idling position.

If either fuel control shaft 8 is moved further 15 toward but not completely to its idling position the respective regulating valve device 60 will again operate as just described to effect a corresponding reduction in pressure of fluid in the respective pipe 61, while if said shaft is returned to its 20 idling position the parts of said regulating valve device will return to the position shown in Fig. 4 in which the release valve 90 will just contact its seat at the time the pressure of fluid in said pipe and in chamber 70 becomes reduced to substantially atmospheric pressure and the regulating 25 spring 79 becomes fully expanded.

It will now be seen that the regulating valve device 60 on each engine will operate to provide in the respective pipe 61 a pressure proportional 30 to the position of the respective fuel control shaft 8, and hence proportional to the amount of fuel supplied to said engine, and it is desired to point out that the regulating valve devices 60 on all of the engines will be initially adjusted the same, so 35 as to provide the same pressures in the respective pipe 61 for the same positions of the respective fuel control shafts 8.

Associated with each of the engines is an 40 equalizing valve device 110 which comprises a casing containing two coaxially arranged and spaced apart flexible diaphragms 111 and 112 of the same areas, which are clamped around their edges in their casing. Between the two dia- 45 phragms is a chamber 113 adapted to be constantly supplied with fluid under pressure through a fluid pressure supply pipe 114. The chamber 113 is formed in two parts divided by a wall 115 having a passage 116 connecting said parts so that the adjacent faces of the dia- 50 phragms 111 and 112 will be constantly subject to fluid at supply pressure. At the opposite face of the diaphragm 112 is a control chamber 117 which is open to pipe 61 leading to the respective pressure regulating valve device 60. At the opposite face of diaphragm 111 is a control chamber 118 which is open to a pipe 119. The pipes 119 at the several engines are all connected to an equalizing pipe 120 which extends to all of said engines.

Each equalizing valve device further comprises 60 a stem 121 extending through chamber 113 and the chamber dividing wall 115 and having one end clamped to the center of diaphragm 112 by fol- 65 lower plates 122 and a clamping nut 123. The opposite end of stem 121 is connected to the center of diaphragm 111 by follower plates 124 and a clamping nut 125 disposed in chamber 118 and connected to said stem. The casing of the device also has a chamber 126 connected to a pipe 127 and separated from chamber 118 by a wall 128, and extending from the exterior of the casing through chamber 126 and wall 128 and having one 70 end open to chamber 118 is a bushing 129 ar- 75 ranged in coaxial relation with the diaphragms

111 and 112 and with the nut 125. The nut 125 has a cylindrical extension 130 slidably mounted in an axial bore provided in the adjacent end of bushing 129, and encircling and having sealing and sliding contact with said extension is a sealing ring 131 carried in a groove in said bushing. The interior of the extension 130 is open to a chamber 132 formed within the bushing 129 and said chamber is open through one or more ports 133 to the casing chamber 126.

One end of chamber 132 within the bushing 129 is closed by a nut 134 secured to said bushing. Secured in the nut 134 is an element 135 having a bore arranged in coaxial relation to the flexible diaphragms 111 and 112, and in said bore is slidably mounted a pin 136. The pin 136 is provided on the end disposed in chamber 132 with a head 137, while on the opposite end of said pin is a fluid pressure release valve 138 arranged to cooperate with a seat on nut 134 for controlling communication between a passage 139 extending along one side of element 135 to chamber 132, and a passage 140 which leads to atmosphere. Interposed between the nut 134 and the stem head 137 is a spring 141 for moving the release valve 138 out of contact with its seat.

A pin 142 projects from the release valve stem head 137 centrally through the cylindrical extension 130 of nut 125 and thence through an opening 143 in said nut to engage a fluid pressure supply valve 144 which is contained in a chamber 145 formed within said nut. The nut 125 has a seat for the release valve 144 around the opening 143, which opening is of greater diameter than stem 142. The supply valve 144 is provided on one end of a fluted stem 146 which is mounted to slide in a bore extending through the nut 125 to a chamber 147 formed below said nut in the diaphragm connecting stem 121. The chamber 147 is connected through one or more ports 148 to the fluid pressure supply chamber 118 between the two diaphragms 111 and 112. In chamber 147 the supply valve stem 146 is provided with a head 149 against which acts one end of a coil spring 150 the opposite end of which is supported by a wall in stem 121. A coil spring 151 contained in chamber 117 acts on the adjacent diaphragm follower plate 122 for opposing movement of the diaphragms 111 and 112 and thereby of nut 125 in a direction against said spring.

In each equalizing valve device 110 it will now be noted that diaphragm 112 is adapted to be subjected in chamber 117 to pressure of fluid provided by the respective pressure regulating valve device 60 through the connecting pipe 61, while diaphragm 111 is adapted to be subjected in chamber 118 to pressure of fluid in the equalizing pipe 120. It will further be noted that spring 150 acting to seat the supply valve 144 will oppose movement of the diaphragms 111 and 112 and the connecting stem 121 by an increase in pressure of fluid in chamber 117 over that effective in chamber 118, while spring 151 will oppose movement of said diaphragms and stem in the opposite direction by a preponderate pressure of fluid in chamber 118. The springs 150 and 151 are so proportioned as to require a definite or fixed differential such as $\frac{1}{10}$ of a pound, between the fluid pressures in chambers 117 and 118, acting in either one direction or in the opposite direction, to move the diaphragms and the connecting stem 121, and this differential will be the same regardless of the pressure of fluid which may be effective in said chambers.

The opposing forces of springs 150 and 151 on diaphragms 111 and 112 and the connecting stem 121 is also adapted to insure movement of these parts to a neutral or lap position in which both the supply valve 144 and the release valve 138 are seated, as shown in the drawing, when the differential between the pressures of fluid in chambers 117 and 118 is less than the chosen differential, above mentioned.

10 Also associated with each of the engines is a selector valve device 152 for selectively conditioning the respective engine either to act as master to which the power output of all of the other engines will be equalized, or for subjugating said engine to control from another selected master engine.

Each selector valve device comprises a casing to which is connected pipe 59 from the vernier diaphragm chamber 49 in the respective governor control motor 28, pipe 127 from the respective equalizing valve device 110, the equalizing pipe 120, and a pipe 153 which is adapted to be charged with fluid at a chosen fixed pressure such as 25 pounds by operation of a suitable fluid pressure reducing valve device 154.

Each of the selector valve devices 152 further comprises valve means, which may be in the form of plug valve 155, and a handle 156 for turning said valve to either a master position in which these parts are shown on engine A or to a slave position in which said parts are shown on engine B. The plug valve 155 has two oppositely arranged cavities 157 and 158 and a through port 159 arranged between said cavities. In the master position of the valve operating handle 156 and valve 155 the cavity 157 will connect the equalizing pipe 120 to pipe 127 leading to the equalizing valve device 110 on the respective engine, and cavity 158 will connect pipe 153 to pipe 59 leading to the respective governor control motor 28, while port 159 performs no function. In the slave position of plug valve 155 the port 159 will establish communication between pipe 59 from the respective governor control motor 28 and pipe 127 leading to the respective equalizing valve device 110, while the ends of the respective pipes 120 and 153 will be closed by said valve.

Operation

50 In operation, let it be assumed that by operation of the operator's control device 33 the pressure of fluid in pipe 32 and thereby in diaphragm chambers 30 in the governor control motors 28 on the several engines is reduced to a degree to permit the parts of said motors to assume idling position, as shown in Fig. 3 of the drawings, to thereby position the respective governor cams 19 in their idling position, as shown in Fig. 2 of the drawing.

Let it further be assumed that the engines have been started and are operating at idling speed, as selected by the operator's control device 33, under which condition the parts of the fuel control system on each engine will assume the position in which these parts are shown in Fig. 2 of the drawing.

With the engines operating at idling speed the pressure regulating devices 60 will be so adjusted by the respective fuel control shafts that at each engine the pressure of fluid in pipe 61 and thereby in diaphragm chamber 117 of the equalizing valve device 110 at that engine will be at substantially atmospheric pressure.

75 Let it further be assumed that pipe 153 extends

ing to all of the engines is charged with fluid at the chosen pressure, of for instance 25 pounds, by operation of the reducing valve device 154, and that engine A is selected as the master engine, against which the power output of the other or slave engine or engines will be matched. With engine A selected as the master engine the selector valve device 152 thereon will be turned to its master position, while on the slave engine B the selector valve device 152 will be turned to its slave position. With the selector valve device 152 on the master engine in its master position opening pipe 50 to pipe 50 fluid at the chosen pressure provided in the former pipe will equalize into the vernier diaphragm chamber 49 of the respective governor control motor 28 but will have no effect upon the operation or positioning of the parts of said motor at this time since the master diaphragm 29 therein is already in its idling position against the stop 57; it being noted that such pressure acts to move said diaphragm against said stop. With the selector valve device 152 on the master engine A in its master position the equalizing pipe 129 will be open to pipe 127 and thus to chamber 126 in the respective equalizing valve device 110. Pipe 120 is also open at all times through pipe 119 to chamber 118 in the equalizing valve device 110.

Let it also be assumed that the equalizing pipe 120 is initially at atmospheric pressure, like pipe 61 on master engine A, as a result of which, chambers 118 and 117 in the equalizing valve device 110 on said engine will both be at substantially atmospheric pressure, so that springs 150 and 151 in said device will hold the parts thereof in their neutral position in which the respective supply valve 144 and release valve 138 are both closed as shown in Fig. 5.

On slave engine B the parts of the equalizing valve device 110 will also be in their neutral position with the equalizing pipe 120 and the respective pipe 61 both at substantially atmospheric pressure. On the slave engine the vernier diaphragm chamber 49 in the respective governor control motor 28 is open through pipe 50 and port 159 in the respective selector valve device 152 to pipe 127 leading to the respective equalizing valve device 110, and let it be assumed that these pipes and chamber are also initially at atmospheric pressure. With the vernier diaphragm chamber 49 in the governor control motor 28 on slave engine B at atmospheric pressure the diaphragm 29 in said motor will also occupy its idling position under pressure of regulating spring 41 the same as if said chamber were charged with fluid as on the master engine A. Thus when the engines are operating at idling speed the supply of fuel thereto will be limited by the position of diaphragms 29 as defined by contact with stops 57 in the respective governor control motors 28.

Now let it be assumed that the operator desires to operate the engines at a speed in excess of idling and to accomplish this operates the control valve device 33 to provide in pipe 32 and thereby in diaphragm chamber 30 of each of the governor control motors 28 fluid at a pressure which on master engine A will deflect the diaphragm 29 out of its idling position and thus out of contact with stop 57 against the opposing force of spring 41 and the chosen fixed pressure of fluid acting in the respective vernier diaphragm chamber 48. Since on slave engine B there is initially no pressure in the vernier diaphragm chamber 49 of the respective governor control motor 28, the pressure of fluid provided in the respective diaphragm cham-

ber 30 will deflect diaphragm 29 away from stop 57 to a greater extent than occurs on master engine A and as a result the governor control cam 19 on the slave engine will be turned out of its idling position to a greater extent than on the master engine. As a result the speed governor 10 on slave engine B will tend to cause operation of the respective fuel control shaft 8 to supply a greater amount of fuel to said engine than is obtained on master engine A by operation of the respective speed governor.

As the fuel control shafts 8 on the two engines are thus operated to increase the supply of fuel thereto, the respective pressure regulating valve devices 60 will be operated to increase in proportion the pressure of fluid in diaphragm chambers 117 of the respective equalizing valve devices 110. On master engine A the equalizing valve device 110 will be operated by the pressure of fluid thus provided in chamber 117 against the pressure of spring 150 to move nut 125 out of seating engagement with the supply valve 144, which will be held against movement at this time since the release valve 138 will be in contact with its seat. When the supply valve 144 on the master engine is thus opened fluid under pressure will flow from chamber 113 between the diaphragms 111 and 112 past said valve to chamber 132 and thence to chamber 126 and from the latter chamber through pipe 127, and cavity 157 in the respective selector valve device 152 to the equalizing pipe 120 leading to the equalizing valve devices 110 on the several engines. On the master engine, the pressure of fluid thus provided in equalizing pipe 120 will flow back through pipe 119 to chamber 118 in the respective equalizing valve device and therein act on diaphragm 111 in opposition to the pressure of fluid in chamber 117 acting on diaphragm 112. When the pressure of fluid obtained in equalizing pipe 120 and acting in chamber 118 of the equalizing valve device 110 on the master engine then becomes increased by flow past the respective supply valve 144 to substantially the same degree as the opposing pressure of fluid in chamber 117 the respective spring 150 will move the diaphragms 111 and 112 against the pressure of fluid in chamber 117 and relative to the supply valve 144 until the nut 125 seats against said valve to prevent further flow of fluid under pressure to the equalizing pipe 120 and thereby to diaphragm chamber 118. It will be noted that spring 150 in the equalizing valve device 110 on master engine A insures closing of the respective supply valve 145 before the pressure of fluid in the equalizing pipe 120 and in the respective diaphragm chamber 118 exceeds that in diaphragm chamber 117, but permits the pressure in said pipe to increase to substantially that provided by the respective regulating valve device 60 to pipe 61 and it will further be noted that this pressure in the equalizing pipe 120 will be proportional to the extent of movement of the fuel control shaft 8 on master engine A out of its engine idling position, and therefore proportional to the amount of fuel supplied to master engine A.

On slave engine B the pressure of fluid provided in the equalizing pipe 120 as above described will be effective in diaphragm chamber 118 of the respective equalizing valve device 110, while in chamber 117 of said device there will be fluid at a pressure controlled by the respective regulating valve device 60 and therefore proportional to the extent of movement of the respective fuel control shaft 8 from its idling position. On the slave engine the fuel control shaft 8 will be initially moved from idling position to a greater degree

than on the master engine, since it was assumed that initially the vernier diaphragm chamber 49 of the respective governor control motor 28 was at atmospheric pressure, and as a result, the pressure of fluid obtained in chamber 117 of the respective equalizing valve device 110 will therefore be greater than the opposing pressure in chamber 118 obtained from the equalizing pipe 120. As a result, on the slave engine B the diaphragms 111 and 112 in the equalizing valve device 110 will move against spring 150 and unseat the nut 125 from supply valve 144 to permit fluid under pressure to flow from chamber 113 to chamber 126 and thence through pipe 127, port 159 in the respective selector valve device 152 and pipe 50 to the vernier diaphragm chamber 49 in the governor control motor 28 on the slave engine. As the pressure of fluid in the vernier diaphragm chamber 49 of the governor control motor 28 on the slave engine then increases such pressure will act through bell crank 54 and rod 36, in conjunction with the pressure of regulating spring 41, to oppose the pre-selected pressure of fluid provided in the diaphragm chamber 30, and since the diaphragm 29 was initially moved against said spring to a position determined solely by the pressure in diaphragm chamber 30, the pressure of fluid now provided in vernier chamber 49 will move the diaphragm 29 back in the direction of stop 57. This movement of diaphragm 29 and thereby of stem 26 in the motor 28 on the slave engine will in turn actuate lever 43 to turn the respective governor control cam 19 in a direction to reduce the pressure of spring 17, whereupon the respective governor 10 will operate to correspondingly turn the fuel control shaft 8 on the slave engine for reducing the supply of fuel to said engine.

As the fuel control shaft 8 on the slave engine is thus operated to reduce the supply of fuel to said engine, the respective pressure regulating valve device 60 will operate to correspondingly reduce the pressure of fluid in diaphragm chamber 117 of the respective equalizing valve device 110, and this operation of supplying fluid to the vernier diaphragm chamber 49 of the respective governor control motor 28 for reducing the supply of fuel to the slave engine, and of reducing the pressure of fluid in diaphragm chamber 117 of the respective equalizing valve device 110, will continue until said pressure becomes reduced to substantially that effective in equalizing pipe 120 and therefore in chamber 118 of said equalizing valve device. When the pressure of fluid in chamber 117 of the equalizing valve device 110 on the slave engine finally becomes reduced to substantially that acting in chamber 118 and in the equalizing pipe 120, spring 150 will move diaphragms 112 and 111 and thereby nut 125 downwardly, as viewed in Fig. 5, until said nut seats against the supply valve 144 for preventing further flow of fluid under pressure to the vernier diaphragm chamber 49 in the respective governor control motor 28. Operation of the governor control motor 28 on the slave engine to reduce the supply of fuel to said engine will then cease, in a position it will be noted, in which the pressure of fluid provided by the respective regulating valve device 60 in diaphragm chamber 117 of the respective equalizing valve device 110 equals substantially that provided in equalizing pipe 120 by operation of the regulating valve device 60 on master engine A, and since the pressure of fluid provided by both of these regulating valve devices is proportional to the amount of fuel supplied to the respective en-

gines the supply of fuel to slave engine B, under the condition above described, will therefore be reduced to substantially the same amount as being supplied to master engine A, whereby the power output of the slave engine will be substantially equalized with that of the master engine.

With the engines operating at a chosen equalized speed or degree of power output as just described, let it be assumed that the operator desires to increase the power output of said engines, and to accomplish this, operates the control valve device 33 to increase the pressure of fluid in the control pipe 32. The governor control motor 28 on master engine A will then operate to cause operation of the respective governor 10 and fuel control shaft 8 to increase the fuel supply to said engine to an amount proportional to the increase in pressure of fluid in diaphragm chamber 30 regardless of the constant pressure of fluid effective in vernier diaphragm chamber 49 of the respective governor control motor 28, and operation of the fuel control shaft 8 on said engine will also operate the respective pressure regulating valve device 60 to provide through pipe 61 in diaphragm chamber 117 of the equalizing valve device 110 on the master engine fluid at a pressure proportional to the increase in fuel supply to the engine. The equalizing valve device 110 on the master engine 8 will then operate to provide in the equalizing pipe 120 fluid at a pressure also proportional to the amount of fuel supplied to the master engine A, as hereinbefore described.

If in response to this operation of the operator's control device 33 to increase the power output of the engines, the governor control motor 28 and the governor 10 on slave engine B should cause operation of the respective fuel control shaft 8 to supply more fuel to the slave engine than is being supplied to the master engine, the pressure regulating valve device 60 on the slave engine will be operated to supply to the respective equalizing valve device 110 fluid at a pressure greater than in the equalizing pipe 120 and said equalizing valve device will then operate to cause operation of the respective governor control motor 28 to reduce the amount of fuel supplied to the slave engine to substantially the same degree as being supplied to the master engine, in the same manner as hereinbefore described.

When the operator's control device 33 is operated to increase the power output of the engines let it be assumed however that the increase in fuel supply to the slave engine B is less than to master engine A. Under this condition the pressure of fluid provided by the regulating valve device 60 on the slave engine through pipe 61 in chamber 117 of the respective equalizing valve device 110 will be less than provided in the equalizing pipe 120 and in diaphragm chamber 118 of said equalizing valve device, so the pressure of fluid in the latter chamber will move the diaphragms 111 and 112 and thereby the nut 125 against spring 151. The supply valve 144 will move with the nut 125 and as a result draw the stem 142 in a direction away from the release valve stem head 137 which will permit spring 141 to unseat the release valve 138.

When the release valve 138 in the equalizing valve device 110 on the slave engine is thus opened fluid under pressure will be released from the vernier diaphragm chamber 49 in the governor control motor on said engine and the consequent reduction in pressure in said chamber will permit pressure of fluid in diaphragm chamber 30 acting on diaphragm 29 to deflect said diaphragm

further in a direction away from stop 57 to cause the respective governor 10 to change the position of the respective fuel control shaft 8 for correspondingly increasing the supply of fuel to said engine, and for operating the pressure regulating valve device 60 on said engine to correspondingly increase the pressure of fluid in chamber 117 of the respective equalizing valve device 110. This operation of the governor control motor 28, incident to release of fluid under pressure from the vernier diaphragm chamber 49, and of governor 10, fuel control shaft 8 and pressure regulating valve device 60 on the slave engine will continue until the pressure of fluid provided by said regulating valve device in chamber 117 of the respective equalizing valve device 110 is increased to substantially the same degree as acting in chamber 118, whereupon spring 151 will move diaphragm 111 and 112 in an upwardly direction and thereby actuate spring 150 and the seated supply valve 144 to move the release valve 138 into contact with its seat to prevent further reduction in the pressure of fluid in the respective vernier diaphragm chamber 49, and to in turn prevent further increase in the supply of fuel to the slave engine.

In the operation just described it will be noted that the position of the fuel control shaft 8 on the slave engine will change for increasing the supply of fuel to said engine until the pressure of fluid delivered by the respective regulating valve device 60 is increased to substantially that provided in the equalizing pipe 120 by the regulating valve device 60 on the master engine A, and since the amount of fuel supplied to the engines is proportional to the pressure delivered by the respective pressure regulating valve devices 60, substantially the same amount of fuel will now be supplied to slave engine B as is being supplied to master engine A.

With the engines operating at a chosen degree of power output the operator may desire to reduce the output of the engines, and to accomplish this will operate the control valve device 33 to reduce the pressure of fluid in control pipe 32 and thereby in diaphragm chambers 30 of the governor control motors 28 on the several engines. On the master engine A the diaphragm 29 will then be deflected by the regulating spring 41 and the pressure of fluid in the vernier diaphragm chamber 49 to a new position, corresponding to the reduction in pressure of fluid in chamber 30, and thereby cause governor 10 on said engine to correspondingly change the position of the fuel control shaft 8. As the position of the fuel control shaft 8 on the master engine is thus changed the supply of fuel to the master engine will be correspondingly reduced and the respective pressure regulating valve device 60 will be operated to reduce the pressure of fluid in diaphragm chamber 117 of the respective equalizing valve device 110 in proportion to the change in position of said fuel control shaft and the reduction in fuel supplied to said engine. When the pressure of fluid in chamber 117 of equalizing valve device 110 on the master engine is thus reduced, said device will in turn operate to reduce the pressure of fluid in the equalizing pipe 120 to substantially that effective in chamber 117 and hence in proportion to the reduction in fuel supply to the master engine.

When the pressure in chamber 30 of the governor control motor 28 on the slave engine B is reduced as above described, said motor will also operate to reduce the supply of fuel to said engine, in accordance with the reduction in pressure in

said chamber, but if for any reason the amount of fuel should be reduced to a degree less than provided on master engine A, the pressure of fluid in chamber 117 of the respective equalizing valve device 110 will become reduced by the respective regulating valve device 60 to a degree below that provided in chamber 118 of said device from the equalizing pipe 120. The equalizing valve device 110 on the slave engine will then be operated to reduce the pressure of fluid in the vernier diaphragm chamber 49 of the respective governor control motor 28 until the respective governor 10 causes the fuel control shaft 8 to obtain a new position in which the respective pressure regulating valve device 60 provides fluid in chamber 117 of the respective equalizing valve device 110 at a pressure substantially equal to that in the equalizing pipe 120. When this condition is obtained the equalizing valve device 110 on the slave engine will operate to prevent further release of fluid under pressure from the vernier diaphragm chamber 49 of the respective governor control motor 28 for stopping operation of said motor, in a position, it will be noted, in which the fuel control shaft 8 on and thereby the amount of fuel supplied to the slave engine will correspond substantially to the position of the fuel shaft and the supply of fuel to the master engine A.

If, when the fuel supply to the master engine is reduced a less reduction occurs on the slave engine, then the equalizing valve device 110 on the slave engine will be operated by pressure of fluid from the respective pressure regulating valve device 60 to increase the pressure of fluid in the respective vernier diaphragm chamber 49 for reducing the supply of fuel to the slave engine, until the pressure of fluid delivered by said regulating valve device corresponds substantially to that provided in the equalizing pipe 120, at which time the fuel supply to the slave engine will substantially equal that to the master engine, as will be apparent without further description.

From the above description it will now be noted that the pressure of fluid in vernier diaphragm chamber 49 of the governor control motor 28 on the slave engine may be either greater or less than that in the corresponding chamber on the master engine at the time the power output of the slave engine is equalized with that of the master engine. The provision of a fixed constantly maintained pressure in the vernier diaphragm chamber 49 of the governor control motor 28 on the master engine thus provides a standard with respect to power output of the respective engine against which the power output of the slave engine is measured or to which it is equalized.

By reversing the positions of the selector valve devices 152 on the master and slave engines A and B, respectively, the equalizing valve device 110 on engine B will be rendered effective to govern the pressure in the equalizing pipe 120 while the apparatus on engine A will then automatically operate to equalize the power output of engine A to that of engine B, as will be evident without further description. In other words, either of the two engines may be selected as the master engine, and if the system embodied more than two engines any one of the engines of the system could be used as the master engine for controlling the others. The mere turning of the selector valve device 152 at the selected engine can either render it the master engine or controllable from another selected master engine.

Further in connection with the equalizing valve

devices 110, it will be noted that the springs 150 and 151 not only insure movement of the dia-phragms 112 and 113 to neutral position in which both the supply valve 144 and the release valve 138 are closed, but also prevent said parts over traveling neutral position, since said springs insure that neutral position will be obtained without increasing pressure of fluid in chamber 118 over that in chamber 117 on the one hand, or without reducing the pressure of fluid in chamber 118 below that in chamber 117, on the other hand. Due to this, operation of the governor control motor 28 and of governor 10 on the slave engine to effect movement of the respective fuel control shaft 8 in a direction to increase the supply of fuel to said engine will be positively stopped when the pressure of fluid delivered by the regulating valve device 60 on said engine may substantially equal but does not exceed that delivered by the pressure regulating valve device on the master engine, so that there will be no oversupply of fuel to the slave engine with respect to that supplied to the master engine. Further, when the fuel shaft 8 on the slave engine is operated to reduce the supply of fuel to said engine the supply will not be reduced to below that to the master engine since the equalizing valve device 110 on the slave engine will obtain its neutral position to stop movement of the respective fuel control shaft 8 when the pressure of fluid in diaphragm chamber 117 becomes reduced by operation of the respective pressure regulating valve device 60 to substantially but not below that provided by the regulating valve device 60 on the master engine. The springs 150 and 151 in thus preventing operation of the equalizing valve device 110 on the slave engine to cause an oversupply, or an undersupply, as the case may be, of fuel to the slave engine with respect to that being supplied to the master engine renders the whole apparatus stable and positive in operation.

Moreover the governor 10 and other parts of the control apparatus on each engine are so designed that said governor will operate the respective pressure regulating valve device 60 to vary the pressure of fluid in chamber 117 of the respective equalizing valve device 110 at least in unison with operation of the governor control motor 28 to effect change in adjustment of said motor, in order that on the slave engine operation of said motor and change in adjustment of the respective governor 10 and fuel control shaft 8 will cease substantially at the instant the respective equalizing valve device 110 is moved into its neutral position. The fuel control shaft 8 on the slave engine will therefore be positively stopped in a position corresponding substantially to that of the fuel control shaft 8 on the master engine as determined by the pressure of fluid in the equalizing pipe 120, so as to ensure that the amount of fuel supplied to the slave engine will be limited to substantially the same amount as supplied to the master engine.

It is desired to further point out that the sensitivity of the equalizing valve device 110 on each engine remains the same throughout the full fuel control range of the respective fuel control shaft 8, that is, regardless of the opposing pressures of fluid which may be acting in chambers 117 and 118, since operation of said device depends only upon a chosen differential between said opposing pressures, and this is very desirable in that it will insure as prompt equalization of the power output of the slave engine to that of the master

engine when the engines are operating against a maximum load, as when operating at idling speed and possibly under no load.

Summary

It will now be seen that the improved control apparatus provides positive automatic equalization of the amount of fuel supplied to each of any desired number of slave engines with the amount of fuel supplied to a preselected master engine, so as to substantially equalize the power output of the several engines, which is particularly desirable where several engines are connected to a common load in order to substantially equally divide the load between the engines.

It will be further noted that any one of the engines can be employed as the master engine merely by turning the selector valve device 152 on that engine to its master position, while leaving the selector valve device 152 on the other engine or engines in its slave position.

Having now described my invention what I claim as new and desire to secure by Letters Patent is:

1. A control apparatus for equalizing the power output of two prime movers comprising an equalizing pipe extending to both of said prime movers, and further comprising for each prime mover, fluid pressure controlled power control means for adjusting the power output of the respective prime mover in proportion to the pressure of such fluid, pressure regulating means adjustable in accordance with operation of said power control means for supplying fluid at a pressure proportional to the power output of said prime mover, equalizing means controlled by opposing pressures of fluid in said equalizing pipe and supplied by said pressure regulating means and operable by a preponderance in pressure provided by said regulating means over that in said equalizing pipe to supply fluid under pressure to another pipe, and operable by a preponderance in pressure in said equalizing pipe over that provided by said pressure regulating means to release fluid under pressure from said other pipe, and operable to bottle up the fluid pressure in said other pipe upon equalization of said opposing pressures, and a two position selector device having one position for connecting said equalizing pipe to said other pipe and for also providing in said fluid pressure controlled power control means fluid at a chosen pressure, and having another position for disconnecting said equalizing pipe from said other pipe and for connecting said other pipe to said fluid pressure controlled means.

2. A control apparatus for equalizing the power output of two prime movers comprising an equalizing pipe extending to both of said prime movers, and further comprising for each prime mover, fluid pressure controlled power control means for adjusting the power output of the respective prime mover in proportion to the pressure of such fluid, pressure regulating means adjustable in accordance with operation of said power control means for supplying fluid at a pressure proportional to the power output of said prime mover, movable power means subject to pressure of fluid in said equalizing pipe acting in opposition to pressure of fluid supplied by said pressure regulating means and movable to one position by the pressure of fluid supplied by said regulating means when it exceeds that in said equalizing pipe, to a second position by pressure of fluid in said equalizing pipe when it

exceeds that provided by said pressure regulating means, and to a neutral position upon equalization of pressures of fluid in said equalizing pipe and supplied by said regulating means, valve means operable by said movable power means in said one position to supply fluid under pressure to another pipe, in said second position to release fluid under pressure from said other pipe and in said neutral position to bottle up the fluid pressure in said other pipe, a source of fluid at a chosen pressure, and a two position selector device operable in one of said two positions to establish two fluid pressure communications one between said other pipe and said equalizing pipe and a second between said source of fluid and said fluid pressure controlled power control means and operable in the other of said two positions to close said communications and to establish a communication between said other pipe and said fluid pressure controlled power control means.

3. A control apparatus for equalizing the power output of two prime movers comprising an equalizing pipe extending to both of said prime movers, a constant pressure pipe extending to both of said prime movers, and valve means for maintaining said constant pressure pipe charged with fluid at a chosen pressure, said apparatus further comprising for each prime mover fluid pressure controlled power control means for varying the power output of said prime mover in proportion to the pressure of such fluid, pressure regulating means adjustable in accordance with operation of said power control means for supplying fluid at a pressure proportional to the power output of said prime mover, equalizing means subject to pressure of fluid in said equalizing pipe acting in opposition to pressure of fluid supplied by said regulating means and movable to one position by pressure of fluid supplied by said regulating means when it exceeds that in said equalizing pipe, and to a second position by pressure of fluid in said equalizing pipe when it exceeds that provided by said regulating means, spring means included in said equalizing means for opposing movement thereof by fluid under pressure to said one and second positions and for moving said equalizing means to a neutral position upon substantial equalization of the pressures in said equalizing pipe and supplied by said pressure regulating means, valve means operable by said equalizing means in said one position to supply fluid under pressure to a third pipe, in said second position to release fluid under pressure from said third pipe and in said neutral position to bottle up the fluid pressure in said third pipe, and a selector device having one position for establishing two communications one between said third pipe and said equalizing pipe and a second between said constant pressure pipe and said fluid pressure controlled power control means, said selector device having a second position for closing said communications and for establishing a communication between said third pipe and said fluid pressure controlled power control means.

4. A control apparatus for equalizing the power output of two prime movers comprising a fluid pressure equalizing pipe extending between said prime movers, a power output regulating pipe for said prime movers, an operator's control device for varying pressure of fluid in said regulating pipe, and a source of fluid at constant pressure at both prime movers, said apparatus further comprising for each prime mover an

adjustable power control element, a fluid motor comprising primary means subject to pressure of fluid in said regulating pipe, and secondary fluid pressure control means, and means controlled by said primary and secondary means for adjusting said power control element in accordance with cooperative effect of pressures of fluid on said primary and secondary means, a fluid pressure regulating device operable by said power control element to provide fluid at a pressure proportional to the power output of said prime mover, equalizing means subject to pressure of fluid provided by said pressure regulating device and in said equalizing pipe and operable by pressure provided by said regulating device when it exceeds that in said equalizing pipe to supply fluid under pressure to another pipe, and operable by pressure of fluid in said equalizing pipe when it exceeds that provided by said pressure regulating device to release fluid under pressure from said other pipe and operable to bottle up fluid pressure in said other pipe upon equalization of pressure in said equalizing pipe with that provided by said pressure regulating device, and a selector device at each prime mover having one position for subjecting said secondary means to pressure of fluid in said source and for at the same time establishing communication between said other pipe and said equalizing pipe, and having a second position for closing said communication and for at the same time subjecting said secondary means to pressure of fluid in said other pipe.

5. A control system for equalizing the power output of a plurality of prime movers comprising an equalizing pipe extending to all of said prime movers, power control means for each prime mover, a fluid pressure controlled motor for each prime mover operable to effect operation of the respective power control means to vary the power output of the prime mover in proportion to the pressure of controlling fluid, fluid pressure regulating means for each prime mover operable by the respective power control means to provide fluid at a pressure proportional to the power output of the respective prime mover, and means at each prime mover including a selector valve having a master control position for providing a chosen pressure of fluid in the respective fluid pressure motor and for at the same time rendering the pressure of fluid in said equalizing pipe variable in accordance with variations in pressure of fluid delivered by the respective fluid pressure regulating means, and having a second position for rendering pressure of controlling fluid in the respective motor variable in accordance with the differential between the pressures in said equalizing pipe and delivered by the respective pressure regulating means.
